UNITED STATES PATENT OFFICE.

MAX ROCKSTROH, OF KLEIN SEDLITZ, NEAR PIRNA, GERMANY.

HIGH-SPEED PRINTING-PRESS.

1,149,688.

Specification of Letters Patent.

Patented Aug. 10, 1915.

Application filed January 6, 1913. Serial No. 740,513.

To all whom it may concern:

Be it known that I, MAX ROCKSTROH, manufacturer, subject or citizen of the Kingdom of Saxony, in the German Empire, residing at Villa Lützow, Klein Sedlitz, near Pirna, Germany, have invented certain new and useful Improvements in and Relating to High-Speed Printing-Presses, of which the following is a specification.

10 My invention relates to high speed printing presses.

In connection with high speed printing presses it is sometimes necessary, for example in case of danger, to suddenly apply the 15 brake with the result that the whole of the mechanism, and particularly the driving gear, is subjected to a very great strain. The brakes hitherto employed only act on the driving gear generally on the fly wheel so 20 that the carriage connected by a connecting rod to the crank shaft has the tendency to continue its movement, with full momentum, when the brake is applied. It is consequently essential with modern high speed 25 presses to destroy the momentum of all moving masses as effectively as possible when the machine is thrown out of operation.

According to the present invention I apply a brake to the reciprocating carriage 30 simultaneously with the brake applied to the fly wheel, so that the momentum of the carriage is directly checked. Various forms of braking devices may be used for this purpose. I may also apply a brake to the printing cylinder so that the cylinder will be 35 stopped in any position when the machine is arbitrarily or automatically declutched. The braking device for the carriage and printing cylinder may be combined so that 40 they operate collectively when the machine is arbitrarily or automatically declutched. The brake devices may be mechanically operated, or by hydraulic or electric power, or other means.

45 The invention is illustrated in the accompanying drawing in which, Figures 1 and 2 are a side elevation and section respectively of a printing press provided with means for braking the carriage. Figs. 3 to 5 are a 50 cross section, longitudinal section and plan view respectively of the gear for actuating the brake shoes. Fig. 6 is a cross section of the brake shoes provided with springs for normally holding them out of action. Figs. 55 7 and 8 are a side and a front view respectively of a hydraulic brake for the carriage.

Figs. 9 to 11 are views to a larger scale of the hydraulic brake. Fig. 12 shows the brake controlling gear. Figs. 13 to 15 show three positions of a brake for braking the printing cylinder.

Referring in the first place to Figs. 1 to 6, the carriage *a* which rolls or slides backward and forward on its bed, is provided on both sides with guide bars *b* adapted to 60 coact with brake shoes *c* the latter being operated by rotation of cam shafts *d* mounted in brackets *e* fixed on both sides of the carriage bed. The shafts *d* are rotated by the clutch gear by means of a system of 65 lever arms *f*, *g*, *h*, *j*, the levers *g* *h* and *j* being fixed to the shaft *i*, and the levers *h* and *j* being connected by links to lever arms *k* and *l*, fixed to the shafts *d*. The brake shoes are normally held out of engagement 70 with the bars *b* by means of springs *m*, as shown in Fig. 6.

It will be seen that with the brake gear as shown in Figs. 1 to 6, the brake shoes acting on the carriage are controlled by 80 mechanical means. The brake shoes may, however, also be controlled by hydraulic power, or the carriage may be hydraulically braked direct. One form of gear for carrying this into effect is shown in Figs. 7 to 85 12. In this case plungers *n* work in cylinders *y* and are adapted to bear against long brake shoes *o*, so that the latter are pressed against the bars *b* fixed to the carriage. The brake shoes are normally held 90 clear of the bars *b* by springs *q* as shown in Fig. 11. The cylinders are connected with one another and with the source of fluid pressure by suitable piping, ports controlled by screws being provided for subsequent escape of the fluid. A plunger *u* inside the pressure generator *t* is actuated by a bell-crank *v* and spring *w*, the latter being in tension in Fig. 12.

Mechanism for braking a printing cylinder is shown in Figs. 13, 14 and 15, Fig. 13 showing a fly wheel brake in combination with the printing cylinder brake, both brakes out of action; Fig. 14 shows the brakes in operation. Fig. 15 is a side view 105 showing the fly wheel and printing cylinder brakes put out of operation by hand, in order to enable the machine to be turned by hand without operating the clutch-shaft.

Fixed to the clutch shaft 1 is a brake 110 cam 2, on which bears an adjustable screw fixed to a lever 3, the latter being pivoted

to a brake lever 4. The lever 4 is pivoted to the bed frame 5, and operates a band brake 6, which acts on the shaft of the fly wheel. To the lever 3 is connected a link 7 which is pivoted to a bell-crank 8 having its fulcrum on the bed frame 5. The bell-crank 8 carries at the end of one arm an adjustable screw 9 which is adapted to bear against the head of a kind of cam lever 10 pivoted to one arm of a double armed lever 11 which is pivoted to the bed frame; the other arm of said lever 11 works in a guide 12 which is fixed to a rod 13. The latter is connected to a lever 14 which actuates the brake hand 15 on the printing cylinder 16.

When the clutch shaft 1 is turned from the position shown in Fig. 13 to that shown in Fig. 14 by means of its handle 1^a the rotation of the cam 2 lifts the screw on the lever 3, and with it the brake lever 4, which operates the brake band 6 so that the fly wheel is braked, at the same time the lever 3, by pulling up the link 7, rocks the bell crank 8 so that the screw 9 on the latter descends, on the head of the lever 10 and rocks the double armed lever 11, so that the other end of the latter raises the rod 13 and actuates the band brake 15 of the printing cylinder 16.

If it is desired to turn the fly wheel by hand the brakes are released by lifting the lever 3 by hand as shown in Fig. 15 whereby the screw thereon is lifted clear of the cam 2 and the screw 9 is also lifted clear of the lever 10, so that both brakes are disengaged. When the machine is clutched again, the brake releasing lever 3 drops back to its original position and the bell crank 8 also returns to its original position, the lever 10 swinging about its pivot, so that the parts resume the position shown in Fig. 13 without the brake being applied to the printing cylinder. It will be seen that with this arrangement of the printing cylinder brake, the latter is automatically applied by declutching the machine, and can be disengaged while the machine is unclutched and automatically returns to its normal inoperative position when the machine is clutched again. Hydraulic, pneumatic or electric brakes may be used in connection with mechanism such as shown in Figs. 13

to 15 for controlling the brakes. It is generally of advantage to combine braking devices for the carriage, cylinder and fly wheel or other part of the actuating mechanism, so that they operate collectively when the machine is declutched automatically or by hand.

Having now particularly described and ascertained the nature of my said invention and in what manner the same is to be performed, I declare that what I claim is:—

1. In braking devices for printing presses of the character described, in combination with the reciprocating table of the press, a guide strip carried by said table, a series of brake shoes disposed along the path of said guide strip, and means for operating said brake shoes simultaneously, substantially as described.

2. In braking devices for printing presses of the character described, in combination with the reciprocating table of the press, a guide strip carried by said table, a series of brake shoes disposed along the path of said guide strip, and means for operating said brake shoe simultaneously, including a cam shaft provided with a series of cams, each adapted to actuate a specific brake shoe, substantially as described.

3. A braking device for printing presses of the character described comprising, in combination, a plurality of brakes, a rotatable rod, a cam on said rod, means for actuating said rod, a brake lever controlling one of said brakes, a bell crank lever pivoted to the brake lever and having one arm engaging said cam, a second brake lever for the second brake, a lever having operative connection with the second brake lever, a second bell crank lever pivoted to swing into and out of engagement with the last mentioned lever, and a link connecting said bell crank levers whereby movement of the first bell crank lever controls the movement of the second bell crank lever.

In testimony whereof I have hereunto set my hand in presence of two subscribing witnesses.

MAX ROCKSTROH.
